UNITED STATES PATENT OFFICE.

HARRY H. LECKLER, OF BROOKLYN, NEW YORK, ASSIGNOR TO EMIL GROSSMAN M'F'G CO. INC., OF BROOKLYN, NEW YORK, A CORPORATION OF NEW YORK.

DESIGN FOR AN AUTOMOBILE BUMPER-BAR BRACKET-ARM.

46,855.

Specification for Design.

Patented Jan. 12, 1915.

Application filed October 22, 1914. Serial No. 868,141. Term of patent 7 years.

To all whom it may concern:

Be it known that I, HARRY H. LECKLER, a citizen of the United States, residing at Brooklyn, in the county of Kings and State of New York, have invented a new, original, and ornamental Design for an Automobile Bumper-Bar Bracket-Arm, of which the following is a specification, reference being had to the accompanying drawings, forming a part thereof, and in which—

Figure 1 is a perspective view taken from one side, Fig. 2 a perspective view taken

from the opposite side, and Fig. 3 an end view taken from the right hand end of Fig. 2, of an automobile bumper-bar bracket-arm embodying my design.

I claim:

The ornamental design for an automobile bumper-bar bracket-arm, as shown.

HARRY H. LECKLER.
